[57] CLAIM

The ornamental design for a ribbon bow, as shown and described.

DESCRIPTION

FIG. 1 is a front elevational view of a ribbon bow constructed in accordance with the present invention;

FIG. 2 is a left side elevational view of the ribbon bow;

FIG. 3 is a top plan view of the ribbon bow;

FIG. 4 is a bottom plan view of the ribbon bow;

FIG. 5 is a right side elevational view of the ribbon bow;

FIG. 6 is a rear elevational view of the ribbon bow;

FIG. 7 is a front elevational view of a ribbon bow constructed in accordance with a second embodiment of the present invention;

FIG. 8 is a left side elevational view of the ribbon bow constructed in accordance with the second embodiment of the invention;

FIG. 9 is a top plan view of the ribbon bow constructed in accordance with the second embodiment of the invention;

FIG. 10 is a bottom plan view of the ribbon bow constructed in accordance with the second embodiment of the invention;

FIG. 11 is a right side elevational view of the ribbon bow constructed in accordance with the second embodiment of the invention; and,

FIG. 12 is a rear elevational view of the ribbon bow constructed in accordance with the second embodiment of the invention.

Applicant hereby disclaims the rectangular back support for the ribbon bow as shown in FIGS. 1-12.
